1

The present invention relates to means for the control of electronic discharges and devices making use of such means.

These means and devices are particularly applicable to high frequencies corresponding to wavelengths of the nature of a meter and a centimeter down to a few millimeters.

The invention has in particular for one of its objects the provision of means whereby the electrons of an electronic discharge may be separated substantially into two groups of distinct mean transversal velocities in accordance with a desired law of control.

Another object of the invention is the provision of means whereby one of these groups of electrons of differing mean transversal velocities may be used as desired with a view to extracting energy from the selected group in an outgoing circuit.

The term transversal velocity of the electrons is understood to mean the perpendicular velocity component in the magnetic field used.

Other objects of the invention further rest in the design of the structure of the electronic discharge devices making use of a controlled separation of the electrons of a discharge as also the means for the production of an electronic discharge whose structure would be particularly favourable in order that this separation might be realised.

In accordance with certain of its characteristics, the invention provides for controlled means of separation of electrons in accordance with their transversal velocities, comprising a magnetic field directed along the general axis of the electronic discharge beam and a high frequency electric field with a direction which is substantially perpendicular to the axis of the said beam.

In accordance with another characteristic of the invention, the electronic beam used does not consist substantially of electrons whose direction of displacement is along the axis of the beam.

In accordance with another characteristic of the invention, means are provided to eliminate the electrons having a certain mean transversal velocity after these have been divided substantially into two groups of differing transversal velocities by an elimination either in accordance with a circle which envelopes the orbits of the electrons of accelerated transversal velocities, or according to their absolute tangential velocity by means of, for example, reflection electrodes.

In accordance with other characteristics of the invention, the electronic discharge devices comprise two or more distinct regions which are

traversed in succession by a single beam of electrons, a magnetic field being directed in accordance with the axis of this beam and an electric high frequency field traversing each of the said regions following a direction which is substantially perpendicular to the axis of the said beam.

In accordance with other characteristics of the invention, the electronic discharge devices comprise two or more distinct regions traversed in succession by a single beam of electrons not including electrons which shift along the axis of the beam at the entry to the first region, a magnetic field being provided parallel to the axis of the said beam and the high frequency electric fields substantially perpendicular to the axis of the said beam individually associated with the said regions.

In accordance with other characteristics of the invention, the electronic discharge devices comprise a first region in which an electron beam penetrates which does not have any electrons whose direction of shift is strictly parallel to the axis of the said beam for the input of the said volume, a magnetic field directed along the axis of the beam and a high frequency electric field substantially perpendicular to the axis of the said beam traversing this region, means for selection at the output of the said region of one of the two groups of electrons which are formed there, and a second region traversed by selected electrons, a high frequency electric field being provided in this region transversally with relation to the axis of the electron beam selected and a magnetic field following the axis of the beam which may be the same magnetic field as that which traverses the first region.

In accordance with other characteristics of the invention, the electronic discharge devices comprise means for the generation of a conic beam of electrons without axial electrons, this beam converging substantially towards the input of a region in which a magnetic field is provided in the axis of the beam and a high frequency electric field substantially perpendicular to this axis, means at the output of this region for the elimination of electrons from one of the two groups being produced whilst the region is traversed, a second region equally provided with a high frequency electric field which is transversal to the axis of the electron beam which is not eliminated, and also crossed by an axial magnetic field which can be the same as that which crosses the first region, and means for the collection of the electrons at the output of the said second region.

In accordance with yet other characteristics of the invention, electronic discharge devices include means for generating a beam of electrons, means modifying the transversal velocities of the electrons of the beam with a view to producing two groups of differing mean transversal velocities, means for the elimination of one of these groups of electrons, and for the use and collection of the electrons of the remaining group.

In accordance with another characteristic of the invention, means for the generation of a conical beam where there is a converging of electrons substantially focussed on the input of the first modifying unit of the transversal velocities of the electrons, consist in an emissive electrode and an electronic concentration lens.

In accordance with another characteristic of the invention, means for the elimination of one of the groups of electrons according to their transversal speed consist in a diaphragm collecting all the electrons whose transversal speeds are greater than a certain value.

In accordance with another characteristic of the invention, means for the elimination of one of the groups of electrons according to their transversal velocities consist in a reflecting electrode which only permits the free transmission to electrons of transversal velocities greater than a certain velocity, and reflecting the electrons of lower velocities in their direction of arrival, or if desired, in a different direction.

In accordance with yet other characteristics of the invention, several beams of electrons not having axial electrons when they are generated are sent parallel in the same direction, or in opposite directions across regions such as the above-mentioned.

According to yet other characteristics the invention provides devices such as those above described, particularly adapted to be associated as oscillators, repeaters, detectors etc. in systems for the transmission of waves by dielectric guides.

The invention will be explained in detail in the following description based on the attached drawings, in which:

Figs. 1 and 2 diagrammatically represent in longitudinal and transverse sections respectively a device modifying the transversal velocities of the electrons in such a way as to obtain two groups of electrons of differing velocities, Fig. 3 indicating the examples of the paths of the electrons at the output of this device;

Fig. 4 shows diagrammatically an example of the discharge device incorporating certain characteristics of the invention with means for the elimination of the electrons of greater transversal velocities, and of using the electrons with low velocities;

Fig. 5 shows diagrammatically in transverse section the paths of the electrons in the system in which the devices according to the invention are used;

Fig. 6 shows diagrammatically an example of the discharge device incorporating certain characteristics of the invention with means for the elimination of the electrons of lesser transversal velocities and of using the electrons of high transversal velocities;

Fig. 7 shows diagrammatically an example of the structure for the generation of a beam of electrons, particularly suitable for use in the devices of the present invention; and

Figs. 8, 9 and 10 show in lateral view, in part in section, in elevation in section, and in detailed view an example of an embodiment of the device

incorporating characteristics of the invention particularly adapted for association with a transmission system with dielectric guides.

The system for the separation of the electrons of a beam into two groups of electrons of varying transversal velocities will be explained with reference to Figs. 1, 2 and 3. This system comprises a pair of parallel conducting plates 1 and 2 between which a beam of electrons 3 is transmitted. A high frequency electric field whose lines of force are indicated at E and provided with arrows indicating the instantaneous direction of the field is applied between these plates. The electrons move, as shown, following a helicoidal path which will be inscribed on a cylinder of a constant radius if they are only subjected to a magnetic field H. Under the influence of a high frequency field, however, the paths of these electrons will be distorted in the following manner, the magnetic field and the electric field being such that an electron describes a circle in a period of the high frequency field.

Considering Fig. 2, an electron 4 at a given instant may have a transversal velocity which is such that it is ready to follow one of the circular paths 5, 6, 7 or 8. If the electron had a velocity which was such that it followed the path 5 of the electric field, it would be retarded at a considered moment where the electric field was in the instantaneous direction represented by the arrows of the lines of force E, and it would describe in this case a path of a smaller radius. When it traverses at 180° of its path, it would again be retarded since the electric field would not then be inverted, and so on in the periods following. In this way such an electron would follow in its passage between the plates 1 and 2 a path such as shown at 9 in Fig. 3. If, on the other hand, the electron had a transversal velocity such that it followed under the action of the magnetic field only, the path 6, it would be accelerated by the electric field periodically with each 180° so that it would describe a total path during its passage between the plates 1 and 2 such as shown in 10 on Fig. 3. If it is to follow one of the paths 7 and 8, it will be alternately accelerated and retarded with each 180° or vice versa, so that its transversal velocity will not in practice be affected on an average by the existence of the electric field.

The operation of the system of invention, will therefore, result in the production of two relatively distinct electron beams, one of accelerated electrons of a greater mean diameter as shown, for example, at 12 in Fig. 4, whilst the retarded electrons will be grouped into a beam of mean diameter which is smaller as shown at 13 in the same figure.

In accordance with other characteristics of the invention, one of these beams will be eliminated and the other used in the following manner: the selected beam will cross another interval comprised, for example, between two parallel plates 14 and 15, between which a high frequency electric field of preferably the same frequency is applied. This system of utilisation is diagrammatically shown in Fig. 5 in transverse section. On this figure simultaneous paths 16, 17 and 18 of electrons 19, 20 and 21 have been shown. These paths are circles and the electrons have all been indicated in the same positions with relation to these paths, that is to say, above their paths in the case shown. These electrons all turn in the direction indicated by arrows 22 and will be subject to alternative transversal shifts such as indi-

cated by the double arrows 23, these alternating shifts being co-phased and in consequence the entire cloud of electrons will oscillate between plates 14 and 15, thus losing the energy which will be collected by the said plate in the form of oscillatory energy which will be used in a circuit not shown, connected to these plates. Their paths will in consequence be more and more narrowed as shown at 24 in Figs. 4 and 6 and will be finally received by an electrode or system of electrodes provided for this purpose and diagrammatically shown at 25 on these two figures. This electrode 25 may be brought to a potential which is such that the electrons are retarded and received at a very reduced velocity with a view to decreasing the power consumption of the device.

The devices in the two Figures 4 and 6 only differ, moreover, by the group of electrons selected for utilisation. The modification systems of the transversal velocities of the electrons and for the use of selected electrons are identical and designated by the same references. In the case of Fig. 4, however, the retarded electrons during their passage between plates 1 and 2 will alone be used, the accelerated electrons being eliminated by means of a diaphragm diagrammatically shown at 26. In the device in Fig. 6 the retarded electrons will, on the other hand, be eliminated by means of a reflector electrode 27 consisting, for example, in a cylinder which is introduced between the two pairs of parallel plates 1-2 and 14-15, the potential of this cylinder being negative with relation to the pair of plates 1-2. The reflected electrons may return in the opposite direction in their direction of arrival, as shown at 28 in Fig. 6, or the reflection electrode may be arranged at a certain angle to the general direction of the electronic beam leaving plates 1-2 so as to send the reflected electrons outside the space between the plates.

In the devices in accordance with the invention, equally the magnetic field should be provided along the entire length of the structure and not simply between the plates 1 and 2.

It should be noted that in the case where the reflected electrons are transmitted between plates 1 and 2 they create in some degree a reactance or return feed of electrons. Such a reactance may be provided if desired by transmitting a beam of electrons between the plates 14 and 15 so that the two plate systems serve simultaneously for input structures and for use at the device.

The means for generating the beam have not been considered up to the present. If the beam of electrons transmitted between the plates 1 and 2 is in its origin a parallel beam, all the electrons will be subjected to a transverse acceleration at the expense of the energy of the high frequency field. It is, consequently, necessary to use a conical electron beam which has no electrons which move axially when they enter the structure, as in such a beam the energy lent to the high frequency field to accelerate half the electrons is equal to the energy supplied by the electrons retarded in the high frequency field. Consequently, the energy absorbed in the high frequency field is substantially nil. Such a beam may, for example, be obtained with the structure in Fig. 7.

In this Fig. 7 an emissive electrode 29 consisting in an annular emissive electrode is arranged behind a diaphragm or concentration electrode 30, which may moreover, consist in a pole-piece of the electromagnet or magnet creat-

ing the magnetic field H. This electrode, or this pole-piece, concentrates the electrons emitted by the electrode 29 into a hollow conical beam 31 which converges approximately on to the input of the plates 1-2. Between the plates 1 and 2 this beam takes the form indicated at 3 on the Fig. 1.

On this Fig. 7 by way of illustration the electric connections of the electrodes 28, 30 and 1-2 have been shown with relation to a source S.

The devices of the present invention may be arranged to operate either as oscillators or as detectors, demodulators, repeaters, frequency changers etc. They may be incorporated in ultra short-wave transmission systems, for example, they may with advantage be applied in systems for the transmission of waves by dielectric guides. An embodiment of the device of this kind whose structure is arranged for adaptation in a transmission system with dielectric guides is shown in Figs. 8, 9 and 10.

In these figures an external sheath 50 which is of metal in the example chosen, but which may equally be of insulating material, is of such a form that it has four open extremities, two by two opposite to one another, 51-52 and 53-54. These extremities are of a suitable form and dimensions to be adapted to the ends of dielectric guides, shown here for greater simplicity in the form of a cylinder with a circular section, although they may have any desired straight section usual in the art of dielectric guides, that is to say, they may be elipsoidal, oval, square, rectangular, polygonal etc. The connections between the extremities 51-54 of the external sheath 50 and the sections of the guide, of which two only are shown on the right-hand side of the design, thus 55 and 56 are constructed so as to be airtight, for example, as shown by means of the insulating junction tubes 57 and 58 sealed at the two extremities on the metallic extremities adjacent to the sheath, and the guide sections, and provided with dielectric transversal airtight cellular constructions such as 59. These cellular constructions may either be of one piece with the insulating junction tubes, or may be sealed in an airtight manner inside the tubes. The insulating tubes are finished inside with a thin metallic layer which is deposited, for example, by pulverisation or projection, or any other suitable manner, and which is shown at 60 on the design on each side of the transversal cellular constructions.

Two metallic tubes 61 and 62 open at either end are arranged inside the sheath between the extremities 51-52 and 53-54 respectively, and are held in place by the insertion of their extremities inside enclosed portions 51-54 of the external sheath. These ends may be split as shown at 63 to permit of freer expansion or contraction under the influence of temperature fluctuations. These metallic tubes 61 and 62 are pierced with apertures 64-65 and 66-67 which are diagrammatically opposed in pairs, the two pairs being opposite one another. Between the tubes 61 and 62 facing the apertures 65 and 66 a hollow conductor cylinder 68 is arranged which is centered on these apertures. Facing the aperture 64 between the cylinder 61 and the envelope 50 is the electron generator electrode structure. This structure comprises a circular emissive filament 69 forming an electrical integral part of a screen 70 introduced between the filament and the sheath and a diaphragm 71 between the filament 69 and the cylinder 61. This

diaphragm may preferably be also electrically an integral part of the filament 69. These electrodes are carried by the cylinder 61 through the medium of the insulating rings 72 and 73 on which the conductor rings 74 and 75 are threaded to which latter the electrodes are fitted mechanically and electrically.

The cylinder 68 is carried by its own electric connection 76, Fig. 9.

On the side of the external opening 67 to the cylinder 62 a collector electrode 77 is placed for the electronic beam which transverses in succession the volume 61 through the openings 64 and 65, the conductor cylinder 68 and the volume 62 across the openings 66 and 67. This collector electrode 77 is preferably supported by its electric connection 78 which crosses the sheath 50 in such a way as to be electrically insulated.

As may be seen on Fig. 9, the electric screen 70, the filament 69 and the diaphragm 71 are mechanically spaced by insulating cross-pieces 79.

A magnetic field parallel to the general direction of the electronic beam emitted by the filament is obtained by means, for example, of an electromagnet whose pole-pieces are indicated at 80 and 81.

A device of this kind operating in the manner explained with regard to Fig. 6 may in particular be used in a system for the transmission of waves by dielectric guides. For this purpose a section of the incoming guide is assumed to be connected to the end 51 of the device and a section of the outgoing guide is shown at 56. In these guide sections the waves arrive in the device by the end 51 as shown by the arrow 82 and leave by the extremity 56 as shown by the arrow 83. Conductor pistons 84 and 85 reflecting the waves are provided in the other guide sections with a view to adjusting the agreement of the volumes by the sliding motion of the pistons. These pistons are preferably in the portions of the device in which the vacuum is not made, but which are filled by a gaseous dielectric, for example, with air. The vacuum is only ensured inside the sheath 50 up to the transversal dielectric cellular constructions, the conducting continuity being realised as nearly as possible between the cylinders 61 and 62 and the sections of the dielectric guide by conducting coatings 60.

In order to use the oscillator device a reflecting piston is also provided in the guide connected to the end 51 and the return coupling of the energy of the high frequency waves necessary for the creation and maintenance of the oscillations is ensured, for example, by a connection with lecher wires 86 terminated by two loops 87 and 88 or in any other suitable manner, for example, by a dielectric guide section.

Another means of return coupling may consist in accordance with another characteristic of the invention in a beam of electrons crossing the two spaces 62 and 61 in the opposite direction of the first beam. For this second beam the role played by the two spaces is, therefore, reversed, the creation of the two groups of electrons of differing transversal velocities being accomplished in the space 62 and the use of the selected group of electrons being made in the space 61.

Devices of this kind are, moreover, in a general way particularly well adapted to the generation or transmission of guided electromagnetic waves of the type termed H_1 , that is to say, of a type where the electric lines of force are transversal with relation to the beam and to the volumes, as shown schematically at 89.

In order to use the device shown as an amplifier on the other hand the return feed circuit 86 may, or may not be suppressed, and the incoming waves are transmitted in the direction shown by the arrow 82, and go out as shown by the arrow 83.

A device of this kind may also be used as a detector, or demodulator by transmitting the modulated carrier waves in the device in the direction of the arrow 82, and by collecting the demodulated or detected waves on the electrode 77. The potentials of the electrodes are adjusted in such a manner as to ensure detection; for example, the electrode 77 may be connected to the cathode through a resistance making use of the demodulation products.

In order to use the tube as a modulator the diaphragm 71 is disconnected from the filament and fed by a modulating potential which, consequently, modulates the intensity of the cathode beam emitted by the filament.

A feed circuit of the electrodes of the device described has been shown by way of example in the case of operation as an amplifier. The reflector cylinder 68 is connected to a negative point of the battery 90 of which another point, less negative, is connected to the filament. The positive end of the battery 90 is connected in parallel to the two cylinders 61 and 62 and a positive intermediary point of the battery is connected to the collector electrode 77 with a view to retarding the electrons in the utilisation cylinder 62 and to collecting them with a very reduced velocity which diminishes the losses in energy of the structure. A filament heating battery 91 is shown connected to a point of the screen 70 and a point of the filament 69. All the feed leads of the generator and collecting electrodes of the beam are insulated in the external sheath as also the cylinder 68 when the potential of the cylinders 61 and 62 is directly applied to the sheath 50 since this latter is assumed to be metallic in the case shown.

The guide section 56 may obviously terminate if desired by a wave radiator system in space, or in waves, or in incoming waves which may originate in a collector system of waves radiated in space.

Although the invention has been described with regard to certain particular embodiments it is clear that it is not in the least limited to these, but is on the contrary capable of numerous modifications and adaptations without leaving its domain.

55 I claim:

1. An electron discharge device including a source of electrons for projecting a stream of electrons in a path, means about said path adjacent said source for generating an alternating electric field substantially transverse to the flow of electrons from said source, means about said path for producing a magnetic field extending generally longitudinally of said flow of electrons from said source, a first electrostatic means about said path adjacent said alternating field generating means for preventing the passage of some of the electrons in said flow, and a second electrostatic means about said path adjacent said first electrostatic means for extracting alternating energy from the electrons which pass said first electrostatic means.

2. An electron discharge device according to claim 1, in which said means for generating an alternating electric field includes a cavity resonator resonant at the operating frequency disposed

in communication with said path between said source and said first electrostatic means.

3. An electron discharge device according to claim 2, in which said second electrostatic means includes a cavity resonator resonant at the operating frequency disposed in communication with said path adjacent said first electrostatic means.

4. An electron discharge device according to claim 3, in which coupling means are provided for feeding back energy from said electrostatic energy extraction means to said electric field generating means.

5. An electron discharge device according to claim 4, in which said coupling is made by means of lecher wires coupled between said cavity resonators.

6. An electron discharge device according to claim 1, in which said electrostatic means for preventing the passage of some of the electrons includes a diaphragm frame disposed generally normal to the flow of electrons and having an aperture generally coaxial with the flow of electrons and coupled to a source of potential negative with respect to the potential of said energy extracting means.

7. An electron discharge device according to claim 1, in which said electrostatic means for preventing the passage of some of the electrons includes a hollow cylindrical member extending generally longitudinally of and coaxial with the flow of electrons and coupled to a source of potential negative with respect to the potential of said energy extracting means.

8. An electron discharge device according to claim 1, in which said source of electrons includes means connected thereto for modulating the output of electrons from said source in accordance with a modulating signal.

9. An electron discharge device according to claim 5, in which said cavity resonators are portions of input and output hollow conducting wave guides, each having apertures generally concentric with the flow of electrons to permit such flow.

10. An electron discharge device according to claim 9, in which adjustable means are provided in said cavity resonators for adjustably varying the oscillating characteristics of said resonators.

11. An electron discharge device according to claim 10, in which said adjustable means includes a plunger or piston adjustably slidable within one of said resonators.

12. An electron discharge device comprising a pair of high frequency electromagnetic wave guides disposed in adjacent relation, a housing enclosing corresponding lengths of said guides, said guides having aligned apertures therethrough, an electron emitter and an electron collector in said housing disposed in spaced relation on opposite sides of said guides and in alignment with said apertures to define an electron beam path transversely of said guides, means to produce a magnetic field axially of said beam path, an annular electrode disposed in said housing between said guides and means to bias said annular electrode at a potential to cause certain of the electrons to leave said beam.

13. An electron discharge device according to claim 12, further including means to terminate each of said guides to one side of said apertures.

14. An electron discharge device according to claim 12, further including lecher wires coupling said guides for return flow of energy therebetween.
